DESIGN FOR A TOY MICROPHONE SET

Joseph L. Metzger, Beverly Hills, Calif.

Application October 22, 1945, Serial No. 123,086

Term of patent 7 years

(Cl. D34—15)

To all whom it may concern:

Be it known that I, Joseph L. Metzger, a citizen of the United States, residing at Beverly Hills, in the county of Los Angeles and State of California, have invented a new, original, and ornamental Design for a Toy Microphone Set, of which the following is a specification, reference being had to the accompanying drawing, forming part thereof.

The essential features of my design reside in the portions shown in full lines in the drawing.

I claim:

The ornamental design for a toy microphone set, substantially as shown and described.

JOSEPH L. METZGER.
